SUPPLY SPOOL FEED

James K. Delano, Rye, N. Y., assignor to Delano Patents Company, Dover, Del., a corporation of Delaware

Application October 11, 1940, Serial No. 360,755

1 Claim. (Cl. 242—45)

This invention relates to the art of processing wire, particularly fine wire.

In one of the applications of this invention, fine wire is continuously drawn under controlled tension, from a supply spool to a take-up spool. Intermediate these spools, the wire is subjected to a series of operations including annealing, coating with an insulating compound, drying and baking of the compound. These operations are effected in an annealing chamber, a coating apparatus, a drying and baking oven. The wire is drawn through these several pieces of equipment by tension applied by means of a capstan around which the wire passes and from which it is delivered to a take-up spool driven by a magnetic clutch, as more particularly described and claimed in my application Serial No. 360,754 entitled "Spooling device for wire," filed on even date herewith, now Patent No. 2,306,045, issued Dec. 22, 1942.

One of the problems met is the maintenance of a controlled tension, predetermined for the particular kind and gauge of wire used, to avoid breakage. If the tension is too great at any point, breakage occurs. If the tension is too low, successful advancement of the wire cannot be achieved since a certain minimum tension is necessary in order that the wire may be drawn and guided through the entire apparatus. The wire must therefore be maintained at all times within a relatively narrow range of tension.

The fact that the tensile strength of the wire, to begin with, may be and usually is very low, that it passes through a series of operations in which its temperature is radically changed, that its direction of movement is frequently changed by contact with numerous guide pulleys and the like, that the tension for causing movement may be applied at a single point near the end of the train of operations, has created a major problem.

One of the objects of this invention is to solve that problem.

The present invention is directed more particularly to the supply spool and its associated mechanism.

One object of the present invention is to devise a positively driven supply spool feed which will cause wire to be supplied from the supply spool continuously at a tension controlled within desired limits.

The principles of the invention will be defined in the claim ultimately appended hereto and will be illustrated by a typical embodiment of the invention as set forth in the following description.

tion taken in conjunction with the drawings, in which:

- Fig. 1 is a plan view;
  - Fig. 2 is an end elevation;
  - Fig. 3 is an elevation partly in transverse section;
  - Fig. 4 is a detail showing the drive shaft, spool mounting and brake drum;
  - Fig. 5 is a diagrammatic view;
  - Fig. 6 is another diagrammatic view showing certain operations and apparatus in cooperation with which the present invention is adapted to be used; and
  - Fig. 7 is an explanatory diagram.
- 15 The series of operations and means for effecting same, to cooperate with which the present invention is adapted, are diagrammatically illustrated in Fig. 6.
- From the driven supply spool 1 the wire passes 20 in contact with guide rolls 2 through an annealing oven 3 (in which it passes around pulleys 4), over guide pulleys 5 to guide pulley 6. Around this guide pulley 6 it makes as many passes, as desired, resulting in a plurality of parallel upper strands 7 (only one of which is shown) and a plurality of parallel lower strands 8 (only one of which is shown). The upper strands pass over rolls 9 in a coating chamber 10 where they are coated with a suitable insulating compound.
- 25 30 The coated wire then passes through a drying and baking oven 15 containing a drying chamber 16 and a baking chamber 17 separated by a wall 18. The wire, provided with its baked coating then passes back over the guide pulley 6 and, directed by pulleys 19 and 20 passes to the capstan 21 and thence to the take-up reel 22.
- The tension which draws the wire through the 35 entire apparatus in cooperation with the delivery of the wire from the driven supply spool 1, is supplied by means of the capstan 21 which is driven by motor 23 acting through a variable speed reducer 24 and a sprocket drive 25, which may also drive the take-up spool 22 through a magnetic clutch, more particularly described and claimed in my copending application Serial No. 360,754 entitled "Spooling device for wire," filed on even date herewith, now Patent No. 2,306,045, as above mentioned.

- 40 The drive shaft 30 is rotatably and demountably carried on the floating bearings 31 and carries a spool of wire 32 which is adapted to be rotated with the shaft 30 through the action of a pin 33 carried by the brake drum 34 and engaging a recess 35 in the hub of the spool. A motor 45 50 55 55 40 is operatively connected with the drive shaft

30 through the pulley 41 on the motor 40, the pulley 42 on the shaft 30 and a belt 43 connecting said pulleys.

A bracket has an arm 44 which is mounted in spaced relation and has an axis substantially parallel with the axis of the drive shaft 30. This arm carries a guide roll 45 rotatably mounted on the said arm 44 in contact with which guide roll wire 46 is drawn from the spool 32 during the operation of the mechanism. The said arm 44 is in turn carried by a lever arm 47 pivotally mounted by means of the collar 48 and pin 49 so that the said lever arm 47 is mounted for oscillation in a plane substantially transverse to the axis of the drive shaft 30 and about an axis parallel to the axis of the drive shaft, and the transverse arm 44 is therefore mounted for oscillation about an axis coinciding with the axis about which the lever arm oscillates. The oscillation of the said transverse arm 44 and guide roll 45 is caused by variations in the tension of wire which is drawn from the spool 32 and in contact with the guide roll. This oscillation occurs through an arc having predetermined limits, the upper limit corresponding to maximum desired tension on the wire and the lower limit corresponding to minimum desired tension (see Fig. 3).

In accordance with the invention wire is simultaneously fed and drawn from the spool 32 around the lower periphery of the guide roll 45 and then in a substantially vertical direction. As tension on the wire increases the guide roll 45 and the transverse arm 44 of the bracket move upwardly through an arc having a radius substantially equal to the length of the lever arm 47 until the guide roll reaches a point on said arc corresponding to the maximum permissible or desirable tension. During this upward movement the spool is not driven and further movement of the guide roll beyond this upper limit would tend to cause undue tension on the wire. In accordance with the present invention the further upward movement of the guide roll is prevented and tension on the wire is reduced by starting the positive rotation of the spool by the motor to cause feeding of the wire. As hereinafter more specifically set forth, the invention includes means for limiting the upward movement of the guide roll by causing positive rotation of the spool at or near a predetermined upper limit of the arc through which the guide roll moves.

As soon as rotation of the spool begins and wire is fed therefrom by the positive rotation of said spool, tension on the wire decreases and the weight of the pivoted guide roll 45 and its supporting lever arm 44 causes the guide roll to descend through an arc the lower limit of which is determined by the minimum desired tension on the wire, and the invention includes means for controlling and predetermining the lower limit of the arc through which the guide roll moves by stopping the motor as the guide roll starts to descend and applying a brake to absorb the momentum of the spool and decelerate its speed at or near said lower limit. When this is done, tension on the wire increases because the spool is no longer positively driven, and the guide roll again moves upwardly until it again reaches its upper permissible or desirable limit, whereupon the positive rotation of the spool by the motor is resumed and the guide roll again descends.

Thus during operation of the apparatus the guide roll continuously moves through an arc having predetermined limits, the upper limit corresponding to maximum desired tension on the

wire and the lower limit corresponding to minimum desired tension. The margin or range of tension on the wire is thus controlled between predetermined limits and these are in turn controlled by the length of the arc through which the guide roll moves.

The present invention includes means for predetermining the said upper and lower limits and therefore predetermining the range of permissible or desirable tension on the wire during operation of the apparatus.

In accordance with the invention the upper limit of tension is predetermined by starting the positive rotation of the spool and the feeding of the wire at a predetermined upper limit of the arc through which the guide roll moves and then discontinuing the positive rotation of the spool, and applying a brake thereto at a predetermined lower limit.

Certain specific illustrative means for predetermining these limits will now be more specifically described.

The lever 47 is fulcrumed at a point intermediate the ends thereof. The said lever has a long arm 50 and a short arm 51 and is mounted for oscillation in a vertical plane about an axis parallel to the axis of the drive shaft and adjacent thereto. At the end of the long arm 50 the said lever carries the transverse arm 44 having an axis parallel to the axis of the drive shaft and as already stated, on this transverse arm the guide roll 45 is rotatably mounted in spaced relation to the drive shaft 30 and the spool 32 carried thereby. The circuit which drives the motor 40 (which in turn drives the drive shaft and spool) includes spring contacts 60 the closing of which closes the motor circuit and thereby causes operation of the motor. The pin 49 on which the lever arm 47 is pivoted carries a cam 61 the angular rotation of which is the same as that of the lever arm. The position of the cam on the pin is so adjusted that the engagement of the cam 61 with the contacts 60 causes closing thereof at any desired upper limit of the arc through which the guide roll moves. The setting of this cam therefore predetermines the upper limit of said arc because the closing of said contacts 60 by clockwise oscillation of said cam 61 causes operation of the motor, positive rotation of the spool and feeding of the wire to the guide roll. Conversely, when the motor causes rotation of the spool and the feeding of the wire to the guide roll and when as a result thereof tension on the wire is decreased and the guide roll descends, oscillation of said cam 61 in a counter-clockwise direction opens said contacts 60 and thereby removes the driving force applied to the spool. The setting and configuration of the cam can therefore be adjusted to open the motor circuit at any predetermined point in the path of travel of the guide roll 45 through said arc. Preferably the setting is such as to open the circuit when the guide roll has travelled a distance about midway between its upper and lower limits. Further rotation of the spool is then dependent largely on its momentum.

The lower limit of tension may be predetermined by applying a positive braking force to the drive shaft at a predetermined lower limit of the arc described by the downward movement of the guide roll and a specific means of accomplishing this will be described as follows:

As will presently appear, it is convenient to have two levers 47 and 47A fulcrumed at points intermediate the ends thereof, as shown in the

drawings, lever 47 having a long arm 50 and a short arm 51, lever 47A having a long arm 50A and a short arm 51A, the respective ends of these arms being connected by transverse members or arms 44 and 44A. The ends of the short lever arms 51 and 51A (and the transverse member 44A connecting these ends) move upwardly and downwardly in consonance with the downward and upward movement of the arm 44 and guide roll 45, respectively, and through an arc the limits of which are determined by the respective lengths of the short and long lever arms and the arc through which the guide roll passes. Adjacent the lower periphery of the brake drum 34 there may be located a brake shoe 62 pivoted at one end by a pin 63 and resiliently connected at the other end, as for example by a spring 64, to the end of the short arm 51A or, as specifically shown in the drawings, to the transverse member 44A connected to the end of the short arm 51A. The braking force applied to the brake drum may be generated solely, as shown, by the force of gravity acting on the guide roll 45, transverse arm 44 and long lever arms 50 and 50A and multiplied by the ratio of the long to the short lever arms. Notwithstanding the relatively low order of magnitude of this force, it is sufficient when multiplied by the leverage effect to cause adequate retardation of the rotation of the spool at a predetermined lower limit of the arc traversed by the guide roll. As the latter moves downwardly the short lever arms 51 and 51A move upwardly in consonance therewith and by suitable correlation of the length of the short lever arms with the brake shoe and its relation to the periphery of the brake drum, the ratio of the long lever arm to the short lever arm, the weights of the lever arms, the transverse arm, the guide roll, the motor speed and the weight of the spool and the wire contained thereon, maximum braking effect may be attained at any predetermined point of the arc traversed by the end of the short lever arms 51 and 51A in their upward movement, which in turn fixes the lower limit of the arc traversed by the guide roll. To enhance the delicacy of control, the short and long lever arms are preferably disposed so that when the guide roll reaches the lower limit of the arc described by it, the short lever arm is disposed at an angle of approximately 30° defined by said short lever arm 51 and a horizontal plane passing through the fulcrum. This makes it possible to apply force to the brake shoe through a line represented by the inclined axis of the spring 64. When the force is initially applied to the brake drum the vertical component of this force is relatively small but as the end of the short lever arm approaches the limit of the arc traversed by it, the axis of the spring 64 moves angularly in a counter-clockwise direction which causes an increase in the vertical component of the force supplied by said spring. Thus rotation of the spool is gradually retarded until tension on the wire approaches its maximum desirable upper limit, whereupon the guide roll 45 ascends, closes contacts 60 and causes the motor to positively rotate the spool.

When this method is carried out by means of the apparatus hereinabove described it will be seen that wire is continuously fed or paid out from the spool in the form of a loop, at one end thereof, which loop passes around the guide roll, the latter being a rotatably mounted element which is suspended in said loop and operates mechanism which in cooperation with said ele-

ment maintains a substantially constant tension on the wire of said loop. The said loop thus forms a reservoir or an accumulator. Wire is fed to one end of said loop and continuously withdrawn from the other end of said loop.

The maximum length of the loop is that which corresponds to the shape of the loop when the guide roll reaches the lower limit of the arc traversed thereby and the minimum length is that corresponding to the shape of the loop when the guide roll reaches the upper limit of the arc described thereby. Thus the average length of the loop may be maintained substantially constant. The apparatus shown in Figs. 1 to 5 is the preferred apparatus for carrying out the method above defined, and this apparatus has been found to successfully solve the problem of continuously feeding very fine wire under a tension controlled within a narrow range so as to provide continuous and successful operation without shut-downs due to breakage or snarling of the wire.

Further details of the apparatus shown in Figs. 1 to 5 will be described as follows:

25 The drive shaft floats upon and is demountably journaled at each end on collar bearings 31 which rotate on roller bearings. The said collar bearings are mounted at each end on housings 90 and 90A, respectively, supported on the platform 91. Integral with the drive shaft is the brake drum 34 at one end thereof carrying a pin 33 which is adapted to engage a hole in the flange 92 of the wire-carrying spool 32. The spool has at the axis thereof a hole running lengthwise of the spool by means of which the spool can be mounted upon and demounted from the arbor 93 which is integral with the drive shaft. A lock nut 94 is provided to secure the spool 32 firmly on the arbor 93.

40 Within the housing, the spring electrical contact members 60 are insulatedly supported on the apron 95, these contacts being also insulated from each other and forming a part of the motor circuit diagrammatically shown in Fig. 5 which includes the motor 40 and the rheostat 96 to control the speed thereof. The motor 40 is suspended from the platform 91 by a swinging joint 97, the weight of the motor and its tendency to swing about this joint causing the pulley thereof 50 to maintain adequate tension at all times on the belt connected to the pulley which drives the drive shaft, in conjunction with a spring 98 which assists in maintaining a suitable taut condition of the belt 43.

55 The bracket carrying the guide roll 45 is pivoted by means of collars and pins (only one of which, 49, is shown), see Figs. 1, 2, 3 and 5, the said pins being carried by the housings 90 and 90A. An extension of the housing 90 carries the stop 99. The housings 90 and 90A which carry the bearings 31 are secured to the platform by flanges 100 and bolts 101.

65 In accordance with this invention from the apparatus point of view there is provided a rotatably and horizontally mounted spindle adapted to rotate a spool of wire carried by said spindle, means to rotate said spindle and spool to deliver wire therefrom and means to apply tension to said wire to draw it from the spool. There is further provided means for periodically and alternately accelerating and decelerating the speed of rotation of the spool. When this is done the tension on the wire in relation to the accelerating and decelerating forces and the times at which they are applied take the form, graphically, of a wave as

shown in Fig. 7. The peaks correspond to the accelerating periods and the valleys to the decelerating periods, since the tension decreases when the speed of the spool is accelerated and increases when it is decelerated.

By varying the accelerating and decelerating forces and the times during which they are applied, the curve shown in Fig. 7 will assume different forms and it is possible to control the tension very delicately within closely controlled limits.

It may be noted that the arm 47 and guide roll 45, used in the preferred form of the invention, move up and down through an arc in accordance with the wave form of curve shown in Fig. 7 and establish the form of the curve by applying the accelerating and decelerating at periods controlled by the cam 49, contacts 60, arms 51, spring 64 and brake shoe 62.

The apparatus and method of this invention have numerous uses other than the one specifically shown. For example, it may be used in co-operation with a coil winding device where it is desirable to deliver wire at periodically varying speeds.

I claim:

A device for feeding wire comprising a horizontally and rotatably mounted drive shaft adapted to rotate a spool of wire carried on said shaft; a lever fulcrumed at a point intermediate the ends thereof and having a long arm and a short arm and mounted for oscillation about an axis parallel to the axis of the drive shaft and adjacent thereto, said lever carrying at the end of its long arm a transverse arm having an axis parallel to the axis of the drive shaft; a guide roll rotatably mounted on said transverse arm and in spaced relation to said drive shaft and spool carried thereby, in contact with which guide roll, wire is drawn from the spool during operation; said transverse arm and guide roll being adapted to be moved upwardly by an increase in the tension on the wire drawn from the spool in con-

tact with said guide roll through an arc to an upper limit of said arc predetermined by the maximum desired tension on said wire, and lowered through the same arc, by gravity and a decrease in the tension on said wire, to a lower limit of said arc predetermined by the minimum desired tension on said wire, the end of said short lever arm being adapted to move upwardly and downwardly in consonance with the lowering and raising of said transverse arm and guide roll; a motor operatively connected to said drive shaft; an electrical circuit which when closed operates said motor; means actuated by the upward movement of said long lever arm to close said circuit, accelerate the rotation of the spool and decrease tension on the wire at about the upper limit of said arc and thereby cause the guide roll to descend; mechanical means connected to said short lever arm to apply braking force to said drive shaft by the upward movement of said short lever arm in consonance with the descent of said guide roll, to decelerate the rotation of the spool, limit the said descent to about the lower limit of said arc and cause the guide roll to ascend, whereby the tension on said wire fed and drawn from said spool is maintained between said maximum and minimum desired limits, said mechanical means comprising a brake drum carried by the drive shaft and an elongated brake shoe pivoted at one end and adapted to swing into and out of engagement with the periphery of said brake drum; and elongated resilient means connecting the other end of the brake shoe with the said short lever arm, the axis of said resilient means and the longitudinal axis of the brake shoe defining an obtuse angle which progressively decreases in magnitude as the short lever arm moves upwardly, whereby the vertical component of the force applied by the brake shoe to the drum progressively increases as said short lever arm moves upwardly.

JAMES K. DELANO.
